ORNAMENT

Jacob Schlesinger, New York, N. Y.

Application February 23, 1939, Serial No. 257,844

7 Claims. (Cl. 40—140)

My invention relates to ornaments and more particularly to monogram jewelry.

Monogram jewelry can be generally divided into two classifications, one of which consists of 5 made-to-order products and the other of which is of the type that is assembled from interchangeable initials or such. The application of the latter type of assemblage has been rather limited to specific shapes of letters if letters 10 alone were utilized or to specific shapes of bases if the letters were mounted thereon. This follows from the fact that the setting of the letters must have anchorage means to retain or engage the letters and since different letters 15 require different disposition of the complementary anchorage means it has been difficult, if at all possible, to devise a foundation which may be so constructed as to receive odd-shaped 20 letters into anchorage means specifically provided in a fixed and definite place in the setting. When therefore, odd-shapes of letters without a base were required, the general practice has been to advert to the expensive made-to-order jewelry since obviously in such case the setting may be 25 bored to accommodate the particular letters which are to be applied thereto.

Bearing the foregoing in mind it is an object of the present invention to devise an ornament of such construction as to permit the assemblage 30 of interchangeable figures thereon which ornament shall simulate the made-to-order variety.

Another object of my invention is to provide such an ornamental device of interchangeable figures wherein the line of demarcation between 35 the figures and the frame which ordinarily surrounds the same shall be eliminated so that the appearance of the assembled device shall be indistinguishable from the made-to-order variety wherein the frame is formed integral with the 40 figures and suitable means are provided on the figures and setting therefor to effect the assemblage.

Another object of my invention is to provide such a device with interchangeable figures 45 wherein the frame which so surrounds the composite figures shall appear to be of one piece thereby furthering the illusion hereinabove described.

Another object of my invention is to provide 50 such a device which is more simple of assemblage than either the present interchangeable type or the made-to-order type while combining advantages of each.

Other objects of my invention will appear 55 from the following description it being under-

stood that the above general statements of the objects of my invention is intended to explain and not to limit it in any manner.

Figure 1 is a front view of a monogram device constructed according to my invention. 5

Fig. 2 is a front view of one of the letters forming the monogram.

Fig. 3 is a side view thereof.

Fig. 4 is a front view of the setting shown in 10 Fig. 1.

Fig. 5 is a section through the line 5—5 of 15 Fig. 4.

Fig. 6 is a rear view of the letter shown in 20 Fig. 2.

Fig. 7 illustrates a similar device of different 25 shape.

Fig. 8 is a rear view of the letter thereof.

Fig. 9 is a section on the line 9—9 of Fig. 1.

Referring to the drawing 10 designates generally the setting for the letters 11 and 12. The 20 setting 10 is formed with an integral border 13 and a recess 14 which may serve as the background for the monogram being seen through the spaces therein. Openings 15, 15a, 15b, and 15c are formed in the recess 14 and it will be 25 noted that the openings 15 and 15b are approximately twice the size of the openings 15a and 15c.

The letter 11 is formed with an integral 30 knurled frame 16 which describes a full semi-circle. Posts 17 are formed on the underside of the frame 16.

The monogram is assembled by inserting the posts 17 of letter 11 into the openings 15, 15b, and 15c, the posts 17 occupying half of the space 35 of openings 15 and 15b. The other letter 12 is similarly inserted. The engagement in this embodiment is frictional as illustrated in Fig. 9 but numerous other engagement or anchorage means are possible as for example causing the posts 17 40 to penetrate the background 10 whereby they may then be bent to prevent disengagement. Engagement means in which the posts 17 extend from the frame 16 in approximately the same 45 plane as said frame and parallel thereto and are retained by tangs on the setting are also contemplated by this invention.

Figs. 7 and 8 illustrate an ornament in which the shape of frame 18 is that of half a heart, the other letter, not shown, bearing the other half. 50

It will be observed that by providing every letter with a frame which is identical with the frame of every other letter, and forming the engagement means on the frame instead of on the letter itself, it is possible to devise a setting 55

which can accommodate any combination of letters interchangeably. When the device is viewed by an observer, it is the natural conclusion that the frame of the monogram is of one-piece construction, the knurling contributing to this illusion, and said frame appears to be part of the setting rather than part of the letters. Furthermore, the integral construction of the letters and the frame seems to lead to no other conclusion but that the ornament has been made to order. Practically every possible shape of setting will lend itself to my invention so that interchangeable letters may be applied thereto.

I have shown a preferred embodiment of my invention but it is obvious that numerous changes and omissions may be made without departing from its spirit. For example, a supplementary background member may be inserted in the recess 14 and provided with similar openings so that the device may be assembled with any background desired. Should a three letter assembly be desired the shapes of the letters and openings can be changed accordingly, the two letter construction being illustrated herein for the sake of clarity. The openings 15 and 15b need not be approximately twice the size of the other openings if the corresponding posts 17 are made half the size.

I claim:

- 30 1. An article of the character described comprising a set of figures, a section of a frame integral with each of said figures whereby said sections cooperate to form a frame for the set of figures when said figures are assembled, a setting, and means to connect said set of figures to said setting.
- 35 2. An article of the character described comprising a set of figures, a section of a frame connected to each of said figures whereby said frame

sections form a complete frame for said figures when said figures are assembled, a setting, and means on said frame sections to connect said figures to said setting.

3. An ornamental device comprising a set of figures, a section of a frame integral with each of said figures, said frame sections being adapted to form a frame for the set of figures when said figures are assembled, posts on said frame sections, a setting, and complementary engaging means for said posts located on said setting whereby said figures may be connected to said setting.

4. An article of the character described comprising a set of figures, a section of a frame integral with each of said figures whereby said sections cooperate to form a frame for the set of figures when said figures are assembled, a support, and means to connect said set of figures to said support.

5. An ornament as set forth in claim 4 wherein said means to connect said set of figures to said support are located on the frame sections of said figures.

6. An article of the character described comprising a set of figures, a section of a frame connected to each of said figures whereby said frame sections form a complete frame for said figures when said figures are assembled, means to connect said figures so as to form a complete ornament provided with a frame as set forth and means to connect said ornament to a support.

7. An article as set forth in claim 6 wherein said means to connect said figures so as to form a complete ornament are located on the frame sections of said figures.

JACOB SCHLESINGER.
